UNITED STATES PATENT OFFICE.

ADAM BERNINGER, OF PITTSBURG, PENNSYLVANIA.

EMBORESSED PICTURE.

SPECIFICATION forming part of Letters Patent No. 781,744, dated June 23, 1903.

Application filed September 4, 1902. Serial No. 122,065. (No model.)

To all whom it may concern:

Be it known that I, ADAM BERNINGER, a citizen of the United States of America, residing at Pittsburgh, in the county of Allegheny and 5 State of Pennsylvania, have invented certain new and useful Improvements in Embossed Pictures, of which the following is a specification, reference being had therein to the accompanying drawings.

10 This invention relates to certain new and useful improvements in embossed pictures, and has for its object the provision of novel means whereby life-like figures are produced upon a suitable background, the figures being 15 composed of single pieces of plastic material provided with coverings molded into the same.

The further object of the invention is to 20 produce a picture embodying figures which are formed of celluloid or light substances that are pressed in shape and modeled to clearly set forth the contour of the face, limbs, and other parts of the body.

With the above and other objects in view 25 the invention further consists in the novel construction, combination, and arrangement, as will be hereinafter more specifically described, and then particularly set forth in the claims, and in describing the invention in detail reference will be had to the accompanying 30 drawings, forming a part of this specification, and wherein like numerals of reference will indicate like parts throughout the several views, in which—

35 Figure 1 is a front view of a picture constructed in accordance with my invention. Fig. 2 is a longitudinal sectional view thereof, taken on the line 2 2 of Fig. 1. Fig. 3 is a like view of a modified form of construction.

40 To put my invention into practice, I provide a suitable background 1, preferably made of a fabric and ordinarily of a fabric having a deep black color—such, for instance, as black velvet. This background is suitably 45 secured upon the back 2 of the frame 3, the latter being preferably provided with a glass or other transparent front 4. Suitably mounted upon the front face of the fabric background are one or more figures 5, which are 50 pressed over a stamp into the outlines of the

person or figure it is desired to represent or imitate. These figures may be secured to the background by stitching or any other suitable ways, but they are preferably composed of celluloid which is subjected to the action 55 of stamp-press in order to impart the desired configuration thereto. In practice I sometimes form the raised figures of different colored celluloid in order to have portions thereof represent the garments and the like. In 60 some instances I also form a portion of the background of celluloid or secure embossed celluloid to the background around the figures.

In Fig. 3 I have shown a celluloid modified 65 form of construction in which I employ, in addition to the raised figures composed of celluloid or light material which is pliable when heated, a covering 6, preferably composed of a fine-silk fabric. This covering is 70 placed directly over the figure and is subjected to the action of the press, together with the figure, so that the fabric is modeled into the configuration of the raised figure and practically forms a part thereof. 75

This application should be considered in connection with an application made by me June 27, 1902, Serial No. 113,516, in which I employ draperies in front of the embossed or raised pictures, said application resulting in 80 the granting of a patent to me bearing date October 7, 1902, No. 710,741.

While I have found celluloid by far the most desirable and preferable material to employ in this connection, yet other light material which could be readily molded to desired shape may be employed, and I therefore do not wish to limit myself to the specific material described. 85

Having fully described my invention, what 90 I claim as new, and desire to secure by Letters Patent, is—

1. As a new article of manufacture, a picture embodying a fabric background mounted in a suitable frame, embossed figures secured 95 thereon composed of single pieces of plastic material, and a covering over said figures molded into the configuration of said plastic material, substantially as described.

2. As a new article of manufacture, a pic- 100

ture embodying a background mounted in a suitable frame, said background having an embossed figure made integral therewith, said figure formed of a single piece of plastic material, and having a covering molded therewith upon the outer face of said figure, substantially as described.

In testimony whereof I affix my signature in the presence of two witnesses.

ADAM BERNINGER.
